CAN FILLING MACHINE

Harry D. Ayars, Syracuse, N. Y., assignor to Continental Can Company, Inc., New York, N. Y., a corporation of New York

Application November 21, 1944, Serial No. 564,457

1 Claim. (Cl. 226—98)

1
The invention has to do with a can filling machine and more particularly with the construction of the pocket provided for measuring a desired quantity of liquid product preparatory to discharging the same into a can.

In my copending application Serial No. 471,272, filed January 4, 1943, now Patent No. 2,362,793, issued November 14, 1944, there is shown and described a machine for filling cans which includes a tank having associated therewith a series of pockets which are filled from the tank and then closed, after which the measured content in the pocket is discharged into a can. Each pocket consists of inner and outer telescoping sections which may be shifted relative to each other for varying the size of the measuring pocket and which may be separated from each other to facilitate cleaning of the same.

An object of the present invention is to provide a sealing means between the telescoping sections of the pocket which permits the two sections to be shifted relative to each other or to be separated and reassembled, which sealing means provides a very tight connection between said telescoping sections when placed in a desired set position.

In the drawings—

Figure 1 is a view in vertical section showing a portion of the filling machine and embodying the improved sealing means used in connection with the telescoping sections of the measuring pocket.

Figure 2 is an enlarged vertical section through the two telescoping sections and the sealing means therefor.

The filling machine includes a center supporting column to which is attached a tank 1, a portion of which is shown in Figure 1 of the drawings. This tank has a bottom wall provided with a series of openings 2 therein. Associated with each opening is a measuring pocket which includes an inner telescoping section 3 and an outer telescoping section 4. Disposed in the tank is a cover plate 5 which remains stationary while the tank is rotatable. This stationary cover plate closes the openings 2 in the bottom of the tank at certain times in the rotation of the tank. The invention has to do with the construction of a measuring pocket and it is not thought necessary to go further into detailed description of the tank and the manner of filling the pockets from the tank.

The outer section 4 of the measuring pocket is provided with a flange 6 which rests upon a support 7 carried by the center column. At the

2
lower end of the outer section is a valve body 8 which has an inner bore corresponding to the bore of the outer telescoping section 4. The lower end of this valve body is closed by a plate 9 which is preferably formed integral with the body member. This plate 9 has a series of discharge openings 10 therethrough which are controlled by a valve 11 yieldingly pressed against the under face of the plate by a spring 12. The valve body 8 is provided with a flange 13. Bolts 14 extend through this flange and are threaded into the support 7. Bolts 15 extend through the flange 6 at the lower end of the outer telescoping section 4 and are threaded into the support 7. Thus the outer telescoping section 4 and the valve body 8 are rigidly secured together and to the supporting member 7 therefor.

The inner telescoping section 3 and the outer telescoping section 4 are dimensioned so as to provide a close fit with sufficient tolerance to permit the sections to be readily shifted axially of each other or to be separated and reassembled for cleaning purposes. The upper end portion of the outer telescoping section is threaded as indicated at 16. A cap 17 is provided with a depending skirt which is likewise threaded so as to cooperate with the thread 16, on the outer telescoping section. This serves as a connection between the cap and the outer section 4. This cap 17 has a portion 18 which overlies the end wall 19 of the outer telescoping section 4. There is an opening through this cap which is dimensioned so as to fit the outer diameter of the inner telescoping section with sufficient tolerance to permit the shifting of the inner telescoping section endwise of the cap.

Located within the cap is a metal ring 20. This ring is dimensioned so as to fit closely the outer diameter of the inner telescoping section 3. This ring is also dimensioned so as to overlie the greater portion of the end wall 19 of the outer telescoping section 4. A ring gasket 21 is placed between the metal ring 20 and the end wall 19. This ring gasket is so dimensioned that when the cap is turned onto the outer section so as to cause the metal ring to forcibly clamp the ring gasket against the end wall 19, said gasket will be forced laterally into very intimate contact with the wall of the telescoping section 3 and this will make a tight fluid joint between the two telescoping sections.

Means is provided for relatively adjusting one of the telescoping sections relative to the other for varying the capacity of the measuring receptacle. This is accomplished preferably by loosen-

ing the cap slightly so as to release the gasket and then shifting the parts to the desired position, after which the cap is turned down so as to again forcibly press the gasket against the end wall of the outer telescoping section and thus deform the gasket sufficiently to bring about a tight sealing connection with the inner telescoping part.

When it is desired to clean the measuring pockets, the cap is loosened so as to free the gasket and the telescoping sections are separated. This may be done by suitable means for raising the tank and lifting the inner section free of the outer section. When it is desired to reassemble the parts, the inner telescoping section will be lowered into the outer telescoping section to the desired extent and then the cap will be turned down to seal the joint between the two telescoping sections.

It is obvious that minor changes in the details of construction may be made without departing from the spirit of the invention as set forth in the appended claim.

I claim:

In a filling machine, a tank and a measuring pocket associated therewith including inner and outer telescoping sections shiftable relative to each other for varying the capacity of the meas-

uring pocket and separable from each other for cleaning purposes, said outer section having a cap threaded on the outer end thereof and overlying the end wall of said section, said cap being provided with an opening through which the inner section passes, a metal collar disposed within said cap and dimensioned so as to make close but sliding contact with said inner section of the pocket and overlying said end wall, a ring gasket disposed in said cap between the end wall of said outer section and said metal ring, said ring gasket being dimensioned so that when pressed between said metal ring and said end wall it will be deformed transversely of its axis and forced into sealing contact with said inner telescoping section:

HARRY D. AYARS.
